(57) **CLAIM**

The ornamental design for portions of a container, as shown and described.

DESCRIPTION

FIG. 1 is a front perspective view of portions of a container according to the invention.

FIG. 2 is a front view of portions of the container of FIG. 1.

FIG. 3 is a rear view of portions of the container of FIG. 1.

FIG. 4 is a left side view of portions of the container of FIG. 1.

FIG. 5 is a right side view of portions of the container of FIG. 1; and,

FIG. 6 is a top plan view of portions of the container of FIG. 1.

The broken lines illustrate portions of the container and form no part of the claimed design.

1 Claim, 6 Drawing Sheets
